UNITED STATES PATENT OFFICE

HARRY HOLIDAY, OF GLENSHAW, AND WILLIAM MCKNIGHT AND JOHN G. CHRISTFIELD, OF BUTLER, PENNSYLVANIA, ASSIGNEES, BY MESNE ASSIGNMENTS, TO THE AMERICAN ROLLING MILL COMPANY, OF MIDDLETOWN, OHIO, A CORPORATION OF OHIO

HEATING FURNACE

Application filed February 2, 1928. Serial No. 251,431.

Our invention relates to furnaces for heating the sliced portions of ingots, which are to be formed into forged steel wheels.

In the manufacture of forged steel wheels, the practice is to form an ingot which is corrugated lengthwise on its surface, with the result of keeping the surface free of cracks and imperfections. The ingot is cut into slices termed "cheeses" in the trade, and the length of the slices taken together with the cross sectional area of the ingot are predetermined so as to provide the correct amount of metal for one wheel in each slice.

The slices or cheeses are heated in a furnace, and the hot cheese is conveyed by a crane to a huge forging press which forms a complete wheel in a single pressing operation. The wheel is then rolled in a mill to form the edges and flanges properly, and the wheel is complete.

One of the major problems in connection with the manufacture of forged steel wheels in the manner above described lies in the heating of the cheese. The heating should be absolutely uniform, as well as controlled as to temperature, so that in the forging operation the flow is even and no defects develop due to some of the metal being harder than the rest.

It is the object of our invention to provide a mechanism within the heating furnace for ingot slices or cheese, particularly for the corrugated ingot cheeses, which will result in an even heating of the slice throughout, and more specifically to provide a feeding device which revolves the cheeses while moving them through the furnace in a predetermined manner so as to expose all faces of each cheese to the products of combustion within the furnace. Also we provide for guides in connection with the feeding devices, such that cheeses of various length can be accommodated.

We accomplish our objects by that certain construction and arrangement of parts to be hereinafter more specifically pointed out and claimed.

In the drawings:—

Figure 1 is a central longitudinal vertical section through the furnace.

Figure 2 is a continuation of Figure 1.

Figure 3 is a vertical cross-section of the furnace taken through the feeding devices.

Figure 4 is a plan view of the bed of the furnace, showing the walls in section.

Figure 5 is a continuation of Figure 4.

Figure 6 is a plan view of one of the guide shoes.

Figure 7 is a side elevation of said guide shoe.

Figure 8 is a central cross section of said guide shoe.

Figure 9 is a perspective of an ingot slice or cheese.

Figure 10 is a cross section through the transfer mechanism.

The furnace to which we have applied our invention is formed as usual in such furnaces of side walls 1, a roof 2, and a bed or hearth 3. The hearth is where the products of combustion are burned, and there is an approach to the hearth which is considerably longer than the hearth, through which approach the products of combustion pass on their way to the flue. This approach has a bed 4, which is provided with (in this instance) two lengthwise openings 5, 5, within which the feeding devices operate.

Along each side of the lengthwise openings 5 are arranged the fixed racks 6, 6, said racks or corrugated plates being so corrugated or toothed as to mesh with the corrugations of an ingot slice or cheese. The racks are set over ingot support bars 6^a, 6^a, which are securely mounted on the furnace framework, and the racks can be changed and new ones inserted without affecting the main support. As indicated in Figure 9, the ingot slices 7 have corrugations 8 lengthwise thereof, and these corrugations mesh with the racks in the same way as a gear meshes with a rack along which said gear is rolled.

At the entrance end of the approach, the ingot slices are introduced through suitable doors, in such a way as to lie across the openings 5, and in mesh with the racks on each side of each opening. If the furnace was single, there would be but one opening, and the feeding devices would be single instead of formed in pairs as shown.

As indicated best in Figure 10, the racks have the crests 6^a of the corrugations at the outer side beveled off as at 6^b, and the approach bed forms shoulders 9, 9, at each side of the racks for each feeding opening. The 10 guide shoes for the ingot slices are arranged to rest on the racks, abut the shoulders on the bed at their outer side, and engage the bevel of the rack corrugation edges, so as to hold them against slipping toward the feeding 15 openings, thus serving as gravity shoes and requiring no bolting in place.

As indicated in Figures 6 to 8, the guides are formed of castings having corrugated 15 bases 10 to fit the racks, with beveled shoulders 11 at the bases of the depressions between corrugations so as to lie over the bevels on the crests of the rack corrugations. The castings have curved faces 12, which 20 engage the ends of the ingot slices and keep them moving in parallel with the racks, and holes 13, by means of which they are manipulated with rods from the side doors of the furnace, at each side thereof.

25 There will be a set of guide shoes with which to equip the furnace for ingot slices or cheeses of each size, and naturally, only one size at once can be run through the furnace at the same time, for best operation.

30 In practice it is often practical to use only one set of guide shoes at one side of the line of feed and permit the slice to engage the shoulder of the bed at the other side. A somewhat unbalanced relation of the slice to the feed bars will not interfere with the feeding 35 operation.

The furnace feed will operate fairly well without the guide shoes if constant inspection and manipulation is maintained, or some 40 other form of guide could be provided, but the particular mode of using shoes which can be manipulated from the furnace doors, and holding the shoes automatically against displacement, has proven itself the most convenient and practical way of keeping the cheeses in line. Our structure, as described, 45 provides against movement of the guide shoes lengthwise of the racks by means of the corrugations, and crosswise of the racks in either direction by the means noted. The 50 shoes are inexpensive, and we are able to avoid the use of adjustable mechanism within the furnace which would be exposed directly to the furnace combustion products, 55 and would deteriorate rapidly by providing shoes of graded sizes.

As a feeding device we provide for long feed bars, one for each feed opening, which bars are actuated from beneath the bed of the furnace approach and move through a circular path within the feed openings.

At a plurality of stations beneath the approach bed we provide for large worm gears 14 mounted in housings 15, and driven by a common worm shaft 16. These worm gears

have on the ends of their spindles 17 which project from the housings, the eccentrics or cranks 18, which have crank pins 19 that move in an eccentric path as the worm gears are slowly revolved.

Large yoke frames 20 are provided, which are journaled by means of slide boxes 21 and slide on the channeled blocks 21^a, said blocks being pivoted on pins 21^b, at each side of the worm gear housings. The yokes also have bushed bearings 22, which engage the crank pins on the gear eccentrics. At the upper ends of the two yoke arms are suitable bearings 23, which serve to mount the feed bars. Thus there are a series of arms 24 arranged 80 on all of the right hand bearings 23, to which the right hand feed bar 25 is secured, and a series of arms 26 arranged on all of the left hand bearings to which the left hand feed bar is secured.

The result of this interconnection and mounting is that the yokes rise and fall and swing to and fro on the blocks 21^a, as actuated by the crank pins, and the bearings 23 traverse an oval or elliptical path defined by the movement of the slide boxes and the movement of the crank pins. The feed bars being connected to a series of the yokes maintain parallelism with each other, and move through an elliptical path.

The feed bars are formed with a series of pockets 27 therein, and the path of movement is controlled so that the feed bars as they rise partially lift the ingot slices or cheeses, but not sufficient to relieve them from meshing with the racks, while the back portion of each pocket in the feed bars pushes the ingot slice so that it rolls along the feed bars. The ingot slice thus cannot slide along, and is not lifted and replaced in the same orientation to the furnace at a new station, but in each instance is caused to roll and present a new orientation to the furnace at each operation of the feeding device. In the case of very large diameter pieces, it will be necessary to start them off with one at every other pocket. Otherwise the shape of the feed bar is such that it will feed ingots of a considerable range of diameters from station to station. In the design shown the ingots will move four steps or corrugations at each intermittent advance.

We have found that the result of rolling the ingot slice along is to permit the products of combustion to thoroughly heat up the said slice, and when the slices reach the hearth of the furnace, which is inclined, the operators push them along with bars. The slices show a tendency to roll on the sloping surface, but rolling of them at the final stage when they are on the hearth and up to full temperature has not been found to be necessary.

The length of the approach with relation to the length of the hearth is a matter of de-

sign, as are the details of the movement whereby the feed bars are given an elliptical path in parallelism with the supports and racks.

5 Having thus described our invention, what we claim as new and desire to secure by Letters Patent, is:—

1. In a furnace for uniformly heating corrugated ingot portions, the combination of 10 rack elements to support the ingot portions in the furnace and to engage the corrugations of the ingot portions, and means for causing the ingot portions to roll in intermittent steps along the rack portions.
- 15 2. In a furnace for uniformly heating corrugated ingot portions, the combination of rack elements to support the ingot portions in the furnace and to engage the corrugations of the ingot portions, and means for causing the ingot portions to roll in intermittent steps along the rack portions, comprising members moving through an elliptical path, insufficient to lift the ingot portions out of mesh with the rack element.
- 20 3. In a furnace for uniformly heating corrugated ingot portions, the combination of a rack element to support the ingot portions in the furnace, said rack element being in two parts with a feed opening between them, said 25 rack element arranged to mesh with the corrugations of the ingot portions, and a feed bar moving in an elliptical path through the said opening, and having pockets therein, said feed bar engaging the ingot portions and 30 moving them in steps without lifting them to relieve the mesh with the racks, for the purpose described.
- 35 4. A feeding and supporting device for a corrugated ingot slice furnace comprising a 40 rack on which the ingot slice rests and with which it meshes, a device arranged to move the ingot slice step by step without lifting it from mesh, with the result of rolling the ingot slice partially during each feeding step, 45 and guiding means for the ingot slice comprising gravity shoes having an ingot guiding face, and corrugations to engage the rack.
- 50 5. A feeding and supporting device for a corrugated ingot slice furnace comprising a 55 rack on which the ingot slice rests and with which it meshes, a device arranged to move the ingot slice step by step without lifting it from mesh, with the result of rolling the ingot slice partially during each feeding step, 60 and guiding means for the ingot slice comprising gravity shoes having an ingot guiding face, and corrugations to engage the rack, said rack having bevels along the outer edge 65 of the same, and beveled shoulders on the guides to engage said shoulders, for the purpose described.
- 65 6. A feeding and supporting device for a corrugated ingot slice furnace comprising a 70 rack formed of interspaced reaches having
- an opening between them for a feeding element, said rack arranged to support and mesh with a corrugated ingot slice, and a feeding element operating in said opening and engaging the ingot slice intermediate its ends, so as to move it without lifting it from mesh with the rack. 75
7. A feeding and supporting device for a corrugated ingot slice furnace comprising a 80 rack formed of interspaced reaches having an opening between them for a feeding element, said rack arranged to support and mesh with a corrugated ingot slice, and a feeding element operating in said opening and engaging the ingot slice intermediate its ends, so as to move it without lifting it from mesh with the rack, said element formed of a lengthwise bar having interspaced elevated portions, and means for moving the bar through an elliptical path having a length equal to 85 the spacing of the elevated portions. 90
8. A feeding device for furnaces for heating ingot slices, which consists in a feed bar having a series of raised portions interspaced approximately the distance of the diameter of an ingot slice to be heated, means for supporting the ingot slice and retaining it crosswise of the feed bar, and means for moving the feed bar in an elliptical path maintaining parallelism with the ingot slice support. 95
9. A feeding device for furnaces for heating ingot slices, which consists in a feed bar having a series of raised portions interspaced approximately the distance of the diameter of an ingot slice to be heated, means for supporting the ingot slice and retaining it crosswise of the feed bar, and means for moving the feed bar in an elliptical path maintaining parallelism with the ingot slice support, said feeding means comprising a series of cranks having pins, a series of means journaled on said pins and connected pivotally to the feed bar, and slide bearings for said means located on the opposite side of the crank pin journal point from the pivotal connections to the feed bar. 100
10. In a furnace for uniformly heating corrugated ingot portions, the combination of a rack element arranged to support the ingot portions and the ingot portions corrugated to mesh with said rack, and mechanical means for pushing the ingot portions along the rack without lifting them from mesh with the rack. 105
